UNITED STATES PATENT OFFICE.

AUGUST D. KUMPF, OF PHILADELPHIA, PENNSYLVANIA.

ELBOW-MAKING MACHINE.

Application filed May 16, 1925. Serial No. 30,803.

To all whom it may concern:

Be it known that I, AUGUST D. KUMPF, a citizen of the United States, residing at Philadelphia, in the county of Philadelphia and State of Pennsylvania, have invented new and useful Improvements in Elbow-Making Machines, of which the following is a specification.

This invention relates to a machine designed for making sheet metal elbows, and an object of the invention is to provide a machine for forming elbows by forming expanded arcuate ribs in straight tubular sections, the ribs being formed in sequence and subsequently creased or folded by compression synchronously with the feeding forward of the top into position for the forming of the succeeding rib which creasing or folding of the ribs results in the step by step arcuate formation of the elbow and also to provide in a machine as specified, corrugated hammers co-operating with a suitable mandrel for corrugating the tubular sheet metal immediately after the creasing of the ribs.

A further object of the invention is to provide in a machine as specified, means for forming and cutting locking tongues through the overlapping edge portions of the sheet metal for locking the sheet metal in tubular formation at the ends.

A further object of the invention is to provide in a machine as specified, means for feeding the tubular sheet metal in step by step portion to the creasing means, which step by step motion controls through a pawl and release mechanism, the clutch structure, and arrests operation of the creasing means immediately after the forming of the last crease, permitting operation of the locking tongue pumping means, and the corrugating hammers, thereby allowing the finishing of the elbow on the single machine, and by a single operator.

A further object of the invention is to provide an improved machine over that disclosed in my Patent No. 1,439,559, issued December 19, 1922, which improvements include among other things, the means for corrugating the elbows.

Other objects of the invention will appear in the following detail description, and in the accompanying drawings wherein:

Figure 1— is a top plan of the improved elbow forming machine.

Figure 2— is a side elevation of the elbow

forming machine having part of the supporting structure broken away.

Figure 3— is an end elevation of the improved elbow forming machine having parts thereof broken away.

Figure 4— is a fragmentary longitudinal section through the elbow forming machine.

Figure 5— is a fragmentary side elevation of a part of the elbow forming machine showing the clutch release mechanism.

Figure 6— is a detail section illustrating a pair of the corrugating hammers used in the machine.

Figure 7— is a fragmentary plan of a part of the corrugating hammer operating structures as indicated by the line 7—7 of Figure 3.

Figure 8— is a front elevation of one of the creasing or ribbing members.

Figure 9— is a side elevation of the creasing or ribbing members shown in Figure 8.

Figure 10— is a front elevation of the second creasing or ribbing member.

Figure 11— is a side elevation of the creasing or ribbing member shown in Fig. 10.

Figure 12— is a view of the elbow showing it in different stages of completion.

Figure 13— is a detail section of the elbow showing the locking tongues.

Referring more particularly to the drawings, the sheet metal from which the elbow is to be formed is first slipped over the cylindrical tube 1 through the circular slots 2 in the front plates 3 and 4, and its inner end is engaged in the annular groove 5 which is formed in the block 6. The block 6 is carried by a suitable carrier 7 which is slidably mounted upon the tube 1 and when the tube of sheet metal from which the elbow is to be formed is first inserted through the circular slots 2 into the groove 5, the carrier 7 is at the outer or forward end of the machine, as clearly shown in Figure 4 of the drawings, and as the sheet metal tube is forced inwardly the carrier is moved rearwardly over the tube, carrying with it the rack 8 which is attached to the upper end of the carrier. The rack 8 has a plurality of relatively long ratchet teeth 9 formed upon its upper surface which co-operate with the pawl 10 in the forming of the elbow. The pawl 10 is pivotally carried by a suitable carrier 11 and it has a latch pin 12 attached thereto which co-operates with a spring operated latch bolt 13. The latch bolt 13 is a part of the spring

latch structure 14 which is of any approved construction. The pawl carrier 11 is pivotally mounted, as shown at 15, to the supporting structure 16, and is connected by 5 links 17 to eccentrics 18 which are mounted upon the shaft 19. The shaft 19 is adapted to be rotated from any suitable power source or prime mover (not shown). When the carrier 7 and rack 8 are being 10 forced rearwardly by the manual insertion of a tube of sheet metal, the pawl 10 is held in the upper position, as shown in Figure 4 of the drawings, by the latch bolt 13 engaging the pin 12. After the tube has been 15 forced rearwardly to the limit of its rearward movement, the pawl 10 is released by the head 20 of a set screw which is inserted in any one of the openings 21 in the rack 8. The position of the set screw 20 is merely 20 regulated, depending upon the number of creases or ridges to be put in the elbow. When the tube of sheet metal has been forced to the limit of its rearward movement, the clutch 22 is thrown into operation 25 in any approved manner, and the tube creasing members or ridge forming members 24 and 25, are rotated, as hereinafter specified, for forming the first crease in the tube and during the forming of this crease, the carrier member 11 moves rearwardly and the pawl 10 drops into position behind one of the straight shoulders of the teeth 9, as shown in Fig. 2 of the drawings, then after 30 this first crease has been formed, the member 11 moves forwardly, which moves the pawl 10 forwardly by the rotation of the eccentrics 18 and this forward movement pushes the carrier 7 forwardly the length of one of the teeth 9, and brings the sheet metal 2 into position for forming the second crease or ridge, as indicated at 23, and 12 of the drawings. When the tube is in position for the forming of the first crease, this crease is formed by the movement of the crease 35 or ridge forming members 24 and 25. The members 24 and 25 are mounted at the forward end of the tube 1 and are carried by pins 26 and 27, which are mounted on the end 28 of the tube 1 and are stationary. The member 24 which moves upward in an eccentric path, as clearly shown in dot-and-dash lines in Fig. 8 of the drawings, is provided with a sliding block 29 which moves 40 vertically in a suitable slot 30, and through which block the pin 26 extends. The creasing member 24 is provided with elongated slots 31 which incline outwardly from the central axis of the creasing member and through which the pins 27 extend. 45 An operating shaft carrying block 32 is mounted in a suitable opening 33 formed in the member 24, and which receives the shaft 34 which is mounted eccentrically on the end of the shaft 35. The shaft 35 extends 50 longitudinally through the tube 1 and is con-

nected by means of the beveled gear 36 and the intermittent beveled gear 37, with the power shaft 19. The creasing member 25 is mounted for movement in an eccentric path laterally of the axis of the tube to be creased 5 and as indicated in the dot-and-dash lines in Fig. 10 of the drawings. The member 25 is provided with a shaft receiving opening 38 through which pin 26 extends, and with openings 39 through which the pins 27 extend. A block 40 is slidably mounted in a rectangular opening 41 and it is provided with a shaft receiving opening 42 through which the operating shaft 34 extends. The perimeters of the members 24 and 25 are flat throughout the major portion of their widths, as shown in Figures 9 and 11 of the drawings, to provide bearing faces 42 and they have creasing rims 43 on their perimeters which are beveled, as clearly shown in Figs. 4, 9 and 11. When the tube of sheet metal has been moved forward one step, the members 24 and 25 are moved in their respective paths, which creases or ridges the sheet metal as indicated at 44 in Fig. 12 of the drawings. Owing to the fact that the paths of movement of the members 24 and 25 are eccentric and that the rims 43 are also eccentric, the ridges or grooves 44 are formed only about a portion of the sheet metal tube, causing the top—if the desired number of creases or ridges have been formed, to assume the elbow shape.

After the first crease or ridge has been formed, the timing of the machine is such that during the forming of the crease, the carrier 11 is moved back with the pawl riding over one of the teeth 9, and just as the crease is completed, the pawl drops behind the straight shoulder 45 of the next tooth 9, and the forward movement of the pawl again begins, which moves the tube forwardly another step, bringing it into position for the forming of the second crease or ridge 44. As the tube is forced forwardly, the substantially triangular shape of the crease or ridge is mashed downwardly or flattened, as shown at 46, in Fig. 12 of the drawings, by the forcing of the tube forwardly through the circular slot 2 and against the inner wall of the front 3.

It will be noted that the inner surface of the front 3 is slightly beveled, as shown at 46, to assist in this flattening or folding over of the ridge or crease. The various ridges or creases are formed subsequently, and are folded over in sequence, and during such operation, the elbow is corrugated or pressure is applied to the folded over ridges, depending upon whether smooth or corrugated elbows are provided.

We will first consider the corrugating of the elbows:

As the tube is moved forwardly for positioning it for the forming of the second or

subsequent creases or ridges, it is moved outwardly over the corrugated mandrel 47, which as clearly shown in Fig. 4 of the drawings, inclines upwardly to compensate for the curvature of the elbow structure. However, the front plate 3 is pivotally mounted, as shown at 48, so that it may swing on the pivots slightly, as the tube is forced forwardly, it being released for such forward swinging movement by the longitudinal movement of the rod 49, which is connected eccentrically to the shaft 19 by a suitable link 50. When the rod 49 moves forwardly, it rocks the stop 51 upon its pivot 52 and moves the set screw 53 out of engagement with the front 3 permitting this front to rock on the pivot 48 to provide a slight yielding movement as the tube is forced forwardly and also to permit the tail 54 of the corrugating hammer 55 to move upwardly beyond the cam lever 56. The hammer 55 and its tail 54 are moved upwardly when they are released by the rocking movement of the plate 3 by means of a suitable spring 57. The tail 54 of the hammer 55 is slidably carried by a suitable guide structure 58 which is in turn carried by the pivoted front plate 3. When the tube is moved forwardly, the rod 49 then returns to its normal position and moves the stop lever 51 into position to prevent rocking movement of the folding plate 3 and brings the end of the tail 54 in the path of the inner edge of the cam lever 56, and also brings the end of the tail 59 of the corrugating hammer 60 in position for engagement by the inner edge of the lower cam lever 61. The cam levers 56 and 61 are connected by suitable cams 62 and 63 to a shaft 64, which is in turn connected by suitable worm gears 65 and 66 with the shaft 19. The cams 62 and 63 are cut so that when the hammer tails 54 and 59 are brought into position to be engaged by the inner edges of the cam levers 56 and 61, respectively, the levers will be rocked upon their pivot 67 to move the hammers 55 and 60 inwardly towards the corrugated mandrel 47 for corrugating a section of the tube of which the elbow is being made. This operation is repeated in sequence to each creasing operation, as above specified, until all of the creases have been made in the tube after which the tube is removed. However, as the last crease in the tube is made, and the pawl 10 has operated the last active tooth 9 of the rack 8, the pawl 10 is raised into the position shown in Fig. 4 of the drawings, by the cam hump 68 which is formed on the sliding bar 69 and engages the roller 70 which is carried by the side of the pawl 10. The bar 69 is slidably mounted upon the side of the rack 8 and is guided in its movement by suitable pins 71 riding in slots 72. It is urged in its forward position, as shown in Fig. 2 of the drawings, by means of a spring 73 and it has an adjustable set screw 74 carried by its forward end which engages the front 4 and moves the bar 69 rearwardly to cause the cam hump 68 to engage the rollers 70 and move the cam upwardly into its inoperative position, in which position it is locked by the latch bolt 13 and pin 12.

When the last crease is formed, the clutch lever 75 is thrown into engagement with the clutch 22 by the engagement of the set screw 76 with rocking pawl 77. The set screw 76 is adjustably carried by an arm 78 which is in turn carried by the head 7, as clearly shown in Figs. 5 and 1 of the drawings. The rocking pawl 77 engages with a pawl 79 which is keyed upon the shaft 80 upon which the clutch lever 75 is keyed. A spring 81 is connected to the clutch lever 75 so that when the pawl 77 is rocked and it is moved out of engagement with the pawl 79, the lever 75 will drop into engagement with the clutch 22 and arrest rotation of the shaft 19. A suitable manually controlled clutch lever (not shown) of any approved type may be used for moving the clutch levers 75 out of engagement with the clutch 22 to permit a single rotation of the shaft 19 and its consequent operation of the various parts connected thereto for the purpose of ending or corrugating the ends of the elbow and for the purpose of forming the locking tongues on the elbow.

After the elbow has been formed and corrugated in the manner heretofore described, the ends of the elbow will be free from corrugations, and as is well known, in the formation of various types of elbows, one of the ends is larger than the other, so as to permit interfitting of the elbow with suitable lengths of pipe. The cam levers 56 and 61 are extended beyond the pivot 67 and have arcuate extensions 85 and 86 formed thereon. The extension 86 is provided with a slot 87 at its pivot through which the extension 85 extends, and each of the arms or extensions 85 and 86 have the tails 88 and 89 of corrugating hammers 90 and 91 respectively, pivoted thereto. The tails 88 and 89 are pivoted so as to permit limited rocking movement thereof, since the meeting edges of the hammers 90 and 91 are cut at acute angles to the tails 88 and 89 respectively, as shown at 92. The inner surface of the hammers 90 and 91 are corrugated, and co-operate with a mandrel 93 which is also corrugated and is carried by a stationary arm 94. After the elbow has been removed from the machine, and off the mandrel 27 and the locking tongues 101 formed as hereinafter specified, the large end is mounted upon the mandrel 93 and the machine is operated for a single rotation of the shaft 19 which brings the hammers 100

90 and 91 together and corrugates the large end of the elbow in a single operation.

It is necessary to chamfer one end of the tube to provide the smaller end and to do this and still corrugate the tube, the mandrel 94 is provided which co-operates with the hammer or die 95. The hammer 95 is attached to the lever 61, while the mandrel 94 is carried by a suitable carrier 96 attached 10 to the supporting structure 97. The mandrel 94 is formed in a quarter section so as to corrugate only one-quarter of the circumference of the small end of the elbow and so as to permit chamfering of this end of the 15 elbow as it is corrugated. The corrugating is done by placing the small end of the elbow upon the mandrel 94 and operating the machine so that when the lever 61 moves downwardly it will bring the hammer 95 20 into striking engagement with the portion of the tube upon the mandrel 94 and corrugate this section. The elbow is then moved to bring an uncorrugated portion thereof over the mandrel 94 and this operation is 25 repeated until the entire small end is corrugated.

If it is so desired, the arm 86 may be extended longer than the extension arm 85, as shown in Fig. 6 of the drawings, so as to 30 bring the hammer tails 88' and 89' on the same angle as the meeting edges 92' of the bosses 90' and 91', thereby eliminating the pivotal and rocking movement limiting structure as described in the preferred form 35 of the invention. The locking tongues 100 and 101 by means of which the overlapping edges of the metal tube are locked together, are formed by the punch structures 102 and 103, one of which is right-hand and the other 40 left-hand. These punch structures include the stationary punch carrying members 104 which have the punches 105 rigidly attached thereto. The punch carrying members 104 are enclosed within tubular shells 106 which 45 are yieldably mounted by means of springs 107. A suitable supporting mandrel 108 is mounted rigidly within each of the cylindrical shells 106. A die member 109 is provided for each of the punch structures, and 50 the die 109 of the lower punch structure 103 is connected by means of a link 110 to an eccentric 111, which eccentric is in turn, connected to the shaft 64. The die 109 of the punch structure 104 is connected by means 55 of a link 114 to the cam lever 56 and is operated by the movement of the cam lever. The tongues 100 and 101 are clamped into the closed locking position by the hammers used in corrugating the elbow.

60 When it is desired to form a smooth or uncorrugated elbow, the hammers 55-60-90-91-94 and 95 are replaced by similar hammers, which have their inner perimeters smooth and free from corrugations. In all 65 other respects, the operation is the same.

Summing up generically, the operation is as follows:

The sheet metal is rolled with its edges overlapping and the tube is forced through the circular slots 2 into the recesses 5 and the carrier 7 and rack 8 are forced rearwardly to their rearmost position. The clutch lever 75 is then moved out of engagement with the clutch 22 and the rotation of the shaft 19 will move the rack 8 and consequently, the tube forward in step-by-step manner, forming the various creases or ridges in the tube at the terminus of each forward step, and during the rearward movement of the pawl 10, into its position to again move the tube forwardly one step, the corrugating operation will take place. Simultaneously, with the forward movement of the tube and carrier 7, the crease or ridge which has just been formed, will be folded over in the manner as above specified, and it will then be hammered flat and tight into position when it is engaged by the corrugating hammers. During the forming of the creases and the subsequent corrugating of the creased portions, only a part of the elbow will be corrugated, leaving the ends smooth and these ends are first connected by forming the locking tongues 100-101 and are then corrugated, the large and small ends upon the mandrels 93 and 94 respectively, in the manner heretofore described, permitting the forming of a complete corrugated elbow on the single machine, and by a single operator.

It is, of course, to be understood, that the invention may be constructed in various other manners and the parts associated in different relations, and therefore, I do not desire to be limited in any manner, except as set forth in the claims hereunto appended.

What I claim is:

1. In an elbow making machine, tube creasing means, corrugating hammers for corrugating sections of the tube, tails on said hammers, cam levers for operating said hammers normally engaging said tails, means supporting said hammers to permit limited lateral movement of the hammers to move them out of engagement with said levers.
2. In an elbow making machine, tube creasing means, means for feeding a tube to said creasing means in a step by step motion, a yieldably mounted front plate for holding over the creases, and means for corrugating sections of the creased tube.
3. In an elbow making machine, tube creasing means, corrugating hammers for corrugating sections of the tube, tails on said hammers cam levers for operating said hammers having edgewise engagement with the ends of said tails, and operating means for operating said cam levers and tube creasing means.

4. In an elbow making machine, tube creasing means, means for feeding a tube to said creasing means in step by step motion, corrugating hammers for corrugating sections 5 of said tube subsequent to the creasing thereof, tails on said hammers, cam levers for operating said hammers having edgewise engagement with the ends of said tails, and means for operating said cam levers and 10 tube creasing means.

5. In an elbow making machine, tube creasing means, means for feeding a tube to said creasing means in a step by step motion, corrugating hammers for corrugating 15 sections of said tube subsequent to the creasing thereof, tails on said hammers, cam levers for operating said hammers having edgewise engagement with the ends of the tails, means supporting said hammers to 20 permit limited lateral movement of the hammers to move them out of engagement with said levers, and means for operating said levers and tube creasing means.

6. In an elbow making machine, tube 25 creasing means, means for feeding a tube to said creasing means in step by step motion, a pivotally mounted front plate for folding over the formed creases, means for corrugating sections of the creased tube, and means for arresting operation of said 30 step by step feeding means after the formation of the last crease in the tube.

7. In an elbow making machine, tube 35 creasing means, means for feeding a tube to said creasing means in step by step motion, a pivotally mounted front plate for holding over the formed creases, and means for arresting operation of said step by step feeding means after the formation of the 40 last crease in the tube.

8. In an elbow making machine, tube 45 creasing means, a rack, a pawl co-operative with said rack for feeding a tube in step by step movement to said creasing means, a movable bar, a cam hump on said bar for moving said pawl out of operative relation with said rack after formation of the last crease in the tube and a retracting spring connected to said movable bar.

50 9. In an elbow making machine, tube creasing means, a rack, a pawl co-operative with said rack for feeding a tube in step by step movement to said creasing means, a movable bar, a cam hump on said bar for moving said pawl out of operative relation with said rack after formation of the last crease in the tube, and latch means for holding said pawl out of operative relation with said rack.

55 60 10. In an elbow making machine, tube creasing means, a rack, a pawl co-operative with said rack for feeding a tube in step by step movement to said creasing means, a movable bar, a cam hump on said bar for moving said pawl out of operative relation

with said rack after formation of the last crease in the tube, a pivotally mounted front plate for folding over the formed creases, and means for corrugating sections of the creased tube.

70 11. In an elbow making machine, tube creasing means, a rack, a pawl co-operative with said rack for feeding a tube in step by step movement to said creasing means, a movable bar, a cam hump on said bar for moving said pawl out of operative relation with said rack after formation of the last crease in the tube, a retracting spring connected to said movable bar corrugating hammers for corrugating sections of said tube, cam levers for operating said hammers, and means for operating said cam levers.

75 12. In an elbow making machine, tube creasing means, a rack, a pawl co-operative with said rack for feeding a tube in step by step movement to said creasing means, a movable bar, a cam hump on said bar for moving said pawl out of operative relation with said rack after formation of the last crease in the tube, corrugating hammers for corrugating sections of said tube, cam levers for operating said hammers, tails on said hammers, said cam levers having edgewise engagement with the ends of said tails, means for operating said cam levers, and means for arresting operation of said operating means after the formation of the last crease in the tube.

80 90 13. In an elbow making machine, tube creasing means, means for feeding a tube to said creasing means in step by step motion, a yieldably mounted front plate for folding over the formed creases, operating means for operating said tube feeding and said tube creasing means, and means for disconnecting said operating means and said tube feeding and creasing means after formation of the last crease in the tube.

95 100 105 14. In an elbow making machine, tube creasing means, means for feeding a tube to said creasing means in step by step motion, corrugating hammers, operating levers for said hammers, means for moving said hammers out of operative relation with said levers at predetermined times, and means for returning said hammers to operative relation with said levers.

110 115 120 15. In an elbow making machine, the combination of stationary punches, movable dies, and yieldable supports for supporting the portion of the tube in position for engagement with said punch and dies.

125 16. In an elbow making machine, the combination of a plurality of corrugating hammers, means for operating said corrugating hammers, a stationary punch and a movable die, and means connecting said die to certain of said corrugating hammer operating means for operating the die.

17. In an elbow making machine, the combination of a plurality of corrugating hammers, means for operating said corrugating hammers, a stationary punch and a movable die, means connecting said die to certain of said corrugating hammer operating means for operating the die, and yieldable supports for supporting a tube in operative relation with said punch and dies. 60
18. In an elbow making machine, a pair of movable corrugating hammers, operating levers for said hammers, means for moving said hammers out of operative relation with said levers at predetermined times, and means for returning said hammers to operative relation with said levers. 65
19. In an elbow making machine, means for creasing a tube, corrugating hammers for corrugating sections of the tube subsequent to the creasing thereof, actuating cam levers for operating said corrugating hammers, and extensions formed on said levers, and crossing each other, said extensions pivoted at their crossing point and corrugating hammers connected to said extensions. 70
20. In an elbow making machine, tube creasing means, means for feeding a tube to said creasing means in step by step motion, a pivotally mounted front plate for folding over the formed creases, means for arresting operation of said step by step feeding means after the formation of the last crease in the tube, corrugating hammers, operating levers for said hammers, means for moving said hammers out of operative relation with said levers at predetermined times, and means for returning said hammers to operative relation with said levers. 75
21. In an elbow making machine, tube creasing means, means for feeding a tube to said creasing means in a step by step motion, yieldably mounted means for folding over the creases, corrugating hammers, operating levers for said hammers, means for moving said hammers out of operative relation with said levers at predetermined times, and means for returning said hammers to operative relation with said levers. 80
22. In an elbow making machine, means for creasing a tube, corrugating hammers for corrugating sections of the tube subsequent to the creasing thereof, actuating cam levers for operating said corrugating hammers, extensions formed on said levers and crossing each other, said extensions pivoted at their crossing point, corrugated hammers connected to said extensions remote from the pivots, means for moving said first named 85
- corrugated hammers out of operative relation with said cam levers at predetermined times. 90
23. In an elbow making machine, a pivotally mounted plate, corrugating hammers slidably carried by said plate, operating levers for said hammers, means for rocking said pivoted plate to move said hammers out of operative relation with said levers at predetermined times. 95
24. In an elbow making machine, a pivotally mounted plate, corrugating hammers slidably carried by said plate, operating levers for said hammers, means for rocking said pivoted plate to move said hammers out of operative relation with said levers at predetermined times, and means for returning said plate and hammers to operative relation with said levers. 100
25. In an elbow making machine, a pivotally mounted plate, corrugating hammers slidably carried by said plate, operating levers for said hammers, means for rocking said pivoted plate to move said hammers out of operative relation with said levers at predetermined times, a support, said levers pivoted to said support, extensions on said levers projecting beyond said pivot, and tube end corrugating hammers carried by said extensions. 105
26. In an elbow making machine, tube creasing means, means for feeding a tube to said creasing means in step by step motion, means for folding over the form creases, a pivotally mounted plate, corrugating hammers slidably carried by said plate, operating levers for said hammers, means for moving said hammers out of operative relation with said levers at predetermined times, and means for returning said hammers to operative relation with said levers. 110
27. In an elbow making machine, tube creasing means, means for feeding a tube to said creasing means in step by step motion, means for folding over the form creases, means for arresting operation of said step by step feed means after the formation of the last crease in the tube, a pivotally mounted plate, corrugating hammers slidably carried by said plate, operating levers for said hammers, means for moving said hammers out of operative relation with said levers at predetermined times, and means for returning said hammers to operative relation with said levers. 115

In testimony whereof I affix my signature,

AUGUST D. KUMPF.
